United States Patent

Des. 235,388
Patented June 10, 1975

235,388

COMBINED BEVERAGE COOLER AND DISPENSER

William Taylor, Columbus, Ohio, assignor to
Ebeo Manufacturing Company, Columbus, Ohio

Filed Nov. 2, 1973, Ser. No. 412,448

Term of patent 14 years

Int. Cl. D15—08

U.S. Cl. D94—3 B

FIG. 1

FIG. 2

FIG. 3

FIG. 1 is a perspective view of a combined beverage cooler and dispenser showing my new design;

FIG. 2 is a front elevational view thereof on a slightly larger scale;

FIG. 3 is a top plan view;

FIG. 4 is a side elevational view; and

FIG. 5 is a rear elevational view thereof.

The side of the combined beverage cooler and dispenser opposite that shown in FIG. 4 is a mirror image of that shown in FIG. 4.

I claim:

The ornamental design for a combined beverage cooler and dispenser, substantially as shown and described.
